DESIGN FOR AN APPLIQUÉ EMBLEM

Charles Emmey, New York, N. Y.

Application February 11, 1937, Serial No. 67,602

Term of patent 7 years

To all whom it may concern:

Be it known that I, Charles Emmey, a citizen of the United States, residing in the city of New York and county of New York, State of New York, have invented a new, original, and ornamental Design for an Appliquéd Emblem, of which the following is a specification, reference being had to the accompanying drawing, forming part thereof.

The figure is a plan view of an appliquéd emblem for use on fabrics and the like showing my design. Said emblem is of no appreciable thickness.

I claim:

The ornamental design for an appliquéd emblem, substantially as shown and described.

CHARLES EMMEY.
